US0D1073448S

(12) **United States Design Patent** (10) **Patent No.:** **US D1,073,448 S**
(45) **Date of Patent:** **** May 6, 2025**

(54) **REEL BUCK APPARATUS**

(71) Applicant: **Jameson, LLC**, Clover, SC (US)

(72) Inventors: **Carlos Fernando Becerra Alvarado**, Charlotte, NC (US); **Brent Wagner**, Bartlett, IL (US)

(73) Assignee: **Jameson, LLC**, Clover, SC (US)

(**) Term: **15 Years**

(21) Appl. No.: **29/963,258**

(22) Filed: **Sep. 16, 2024**

Related U.S. Application Data

(63) Continuation of application No. 18/520,678, filed on Nov. 28, 2023.
